DRY-PLACER MACHINE

Application filed December 12, 1927. Serial No. 239,432.

This invention relates to improvements in placer mining machines and has reference more particularly to a machine that can be used without water and which will therefore be referred to as a dry placer mining machine.

In many parts of our country there are large deposits of sand and gravel which contain gold in considerable quantities, but these are far removed from water supplies and therefore are not available for treatment in the usual way.

It is the object of this invention to produce a machine that can be used for the separation of gold from sand and gravel in a dry state and which therefore can be employed in such places where gold is found, but water is lacking.

This machine, briefly described, comprises a crusher which serves to reduce the sand and gravel to fine particles and to deliver them to a bar mill where they are still further reduced. The bar mill has one end connected with a rotary screen whose other end terminates adjacent a set of movable louvers which in operation are amalgamated and arranged with their amalgamated surfaces facing the rotary screen. Means is also provided for producing a blast of air through the screening device, which will direct the sand and gold particles onto the amalgamated surface of the louvers.

As the gold that is found in dry sands or gravel, to which reference is herein made, is usually very fine and is often referred to as flour gold, it will be carried by the air current towards the amalgamated plates and will become attached to these, whereas the sand and inert matter will not be attracted by the amalgam and thereby a separation will be effected.

In order more fully to describe this invention, reference will now be had to the accompanying drawings in which the preferred embodiment thereof has been illustrated and in which:

Fig. 1 is a side elevation of the improved machine, portions thereof being shown in section to better disclose the construction;

Fig. 2 is a transverse section through the rotating screen, taken on line 2—2, Fig. 1;

Fig. 3 is a transverse section through the bar mill taken on line 3—3, Fig. 1;

Fig. 4 is a longitudinal diametrical section taken on a plane represented by line 4—4, Fig. 1;

55

Fig. 5 is a section taken on line 5—5, Fig. 4;

Fig. 6 is a section taken on line 6—6, Fig. 5, and shows the air manifold, parts thereof being broken away so as to better disclose its construction; and

60

Fig. 7 is a section taken on line 7—7, Fig. 1, and illustrates the manner in which the frame containing the movable louvers is held in place.

The machine is supported on a framework 65 which has been illustrated as formed from a plurality of pipe sections. In the embodiment illustrated the framework is provided with four legs 1, 1 and 2, 2. These legs form

two pairs and the legs indicated by numerals 70 1 are shorter than those indicated by numerals 2.

The upper end of each leg is provided with an L 3 to the ends of which the transverse frame members 4 are connected, Fig. 5. Side bars or pipes 5 extend from one leg as-

sembly to the other and these side bars or pipes are provided with a plurality of grooved pulleys. The pulleys which have been designated by numeral 6 are of consider-

able size and are freely rotatable on bars 5, 75 but are held against longitudinal movement by means of collars 7. A smaller grooved pulley 8 is secured to each bar 5 near the

support assembly formed from legs 1, 1 and is held against longitudinal movement by means 80 of the collars 9. As the two parallel side bars 5 are each provided with pulleys in the

manner shown in Fig. 1, there will be three pairs which are placed opposite each other. These pulleys serve as a support for rotatable 90

cylinders 10 and 11. These cylinders are of different diameters, the one indicated by num- 95

eral 10, which contains the rotatable screen, being of greater diameter than the cylinder 11, which contains the bars 12. The adja-

cent ends of these cylinders are connected by brackets 13 in the manner shown in Fig. 4. A spider 15 is secured to the inner end of cylinder 11 and has attached to it a screen 16. For the purpose of attaching this spider 100

in place, it is provided with a plurality of radially extending brackets 17, whose ends are bent at right angles to the plane of the spider and are perforated for the reception

of the securing rivets 19. The other end of cylinder 11 has secured to it a cover or closure 20, which is preferably hinged at 21 and is held in closed position by means of a hasp 22, that is engaged by a staple 23. This end closure is provided with a circular opening 24, through which the spout 25 projects into the interior thereof. The spider 15 and the end closure 20 serve as guides for the bars 12 and keep these from moving longitudinally to any great extent.

A ring gear 26 is secured to the cylinder 11 in the manner shown in Fig. 1. The screening cylinder 10 has secured to it a cylindrical screen 27, which is of somewhat smaller diameter than the interior of cylinder 10 and is spaced from the latter by means of brackets 28, Fig. 2. Cylinder 27 is substantially the same length as cylinder 10 and is divided into four sector shaped compartments by means of diametrical screens 29. These screens are preferably spiraled in the manner shown in Fig. 2, although this is not considered to be absolutely essential. A band 30 is secured to the outside of cylinder 10 and serves as a track which cooperates with the grooved pulleys 8 and two bands 31 are secured to the outer surface of cylinder 11 and serve as tracks which cooperate with the grooved pulleys 6. It is now apparent that the assembly comprising cylinders 10 and 11 can be rotated as it is supported by the rotatable pulleys 6 and 8. For the purpose of rotating this assembly a drive shaft 32 has been provided. This shaft is journaled at one end in a bearing 33 and at the other end in a bearing 34. The bearing 34 is supported on brackets 35, one end of each of which is secured to one of the legs 2 by a clamp 36 and the other end of each of which is secured to the side bar 5 by means of a corresponding clamp 37. The outer end of shaft 32 is provided with a belt pulley 38 to which power may be transmitted by means of a belt from some prime mover such as an internal combustion engine or an electric motor. Secured to shaft 32 is a gear wheel 39 that cooperates with the ring gear 26 for the purpose of rotating the assembly comprising the two cylindrical members 10 and 11. The other end of shaft 32 is provided with a gear 40 that cooperates with a pinion 41 on the fan 42. The exhaust port of this fan is connected by means of a tubular member 43 to a circular manifold 44. This manifold surrounds the cylinder 11 and is located with one side close to the adjacent end of cylinder 10. The side nearest cylinder 10 is provided with a plurality of openings 45 which are spaced equidistantly around the circular manifold. When the fan is in rotation it serves to force air under pressure into the manifold and this will pass through the openings 45 into the interior of cylinder 10 and produce a strong air current which flows from the manifold

towards the open end of the screen that lies adjacent to the amalgamating plates which will now be described.

Secured to side bars 5 by means of brackets 46 is a rectangular frame 47 whose two vertical sides are parallel and are provided with openings for the reception of the bearings 48 at the ends of the louvers 49. These louvers are pivoted at each end in the manner shown and are of such width that when they are moved into substantially parallel position their adjacent edges will overlap in the manner shown in Fig. 5. In order to move these louvers simultaneously and all to the same extent, their outer edges are connected by a rigid bar 50 in the manner shown in Fig. 5. A crank 51 is secured to the outer end of one of the pivots 48 and by means of this crank the louvers can be rotated about their pivots from the full line to the dotted line position shown in Fig. 5. Located directly beneath this louver frame is a pan 53 whose rear side wall has an upward extension 52 that prevents gangue from entering the pan. The purpose of this pan is to catch the gold and other metallic values which are scraped from the louvers during the clean-up operations in a manner which will be hereinafter more fully described. The manifold 44 and the frame containing the louvers are held in place by means of diagonal braces in the manner shown in Fig. 1. At the end of the device to which the material is fed there has been indicated in a more or less diagrammatic manner a crusher comprising a plurality of pairs of rollers which are rotatably mounted in sliding bearings 55 that are acted upon by springs 56 to move them towards each other. These rollers are spaced different distances apart, the lower pair of rollers coming into contact with each other. As the material is fed into the hopper 57, it will pass downwardly between these rollers and be reduced to fine particles. The actual construction of this roller assembly has not been shown in detail for the reason that it does not form a part of this invention and has merely been shown for the purpose of facilitating the description of the operation.

Let us now assume that the device has been assembled in the manner described and that the sides of the louvers 49 that are nearest to the screen cylinder have been properly amalgamated. Power is now applied to pulley 38 so as to rotate the bar mill and the screen. Material can now be fed from the hopper 57 through the rollers and into the bar mill where it will be still further reduced in size. As the parts are constantly rotating, the ground dry materials comprising sand and metal values, are caused to roll around where the fine particles will be caught by the air stream and carried along into and through the screen section. When the particles enter the screen section they will be subjected to a

strong breeze from the air entering through the openings 45 in the manifold and the lighter particles will be carried along and finally strike the amalgamated surface of 65 the louvers where any gold, silver or other metal will be attracted by the mercury amalgam and secured to the louvers. The rotating screens 27 and 29 will serve to separate the large particles from the smaller ones and 70 10 the gangue will pass outwardly through the space between the end of the cylinder 10 and the adjacent side of the louver frame whereas the finer particles and the fine metallic values will, as above indicated, be forced 15 against the amalgamated surface of the louvers. After the machine has been in operation for some time and is to be cleaned, the louvers are rotated from the full line position shown in Fig. 5 to the dotted line position 20 and this brings the amalgamated surfaces into accessible position. These are then wiped with a brush, thereby removing the accumulations from the previous operations. The mercury amalgam containing the metallic values drops into the pan 51 from which 25 it can be removed from time to time.

The screen 27 and the screens 29 serve to agitate the materials. If any of the finer materials pass through screen 27, they will 30 be carried by the rotating cylinder for some distance and will then fall into the interior of cylinder 27. Any heavy coarse material that falls on the screens 29 will roll along this screen outwardly onto screen cylinder 27 and 35 will roll along the latter for a distance of ninety degrees and will then roll along one of screens 29 inwardly towards the center. This movement of the heavy particles will loosen all the light material which will then 40 be caught in the stream of air and blown onto the amalgamated plates.

It will be observed from the above description that this machine is so constructed that it will operate without the use of water, in fact 45 the drier the material the more successful is the operation, as it is essential that the material shall be formed into a dry dust that will be entrained in the air current and carried against the amalgamated surfaces. This 50 machine is therefore very well adapted for use in arid districts where water is scarce as the operation takes place with dry materials.

Having described the invention what is claimed as new is:

55 1. A device for separating gold from dry auriferous sands, comprising, in combination, a supporting frame, a cylindrical member supported on the frame by means which permits it to rotate about an inclined axis, means for rotating the cylindrical member, means for delivering powdered sand and gold to one end of said cylindrical member, means for producing a strong blast of air through the interior of the cylindrical mem-

ber, a stationary frame supported by the first mentioned frame at the delivery end of the cylindrical member and a plurality of inclined, spaced overlapping amalgamating plates secured to the stationary frame, said plates having their amalgamated surfaces adjacent the cylindrical member. 65 70

2. A device for separating gold from dry auriferous sands, comprising, in combination, a supporting frame, a cylindrical member supported on the frame by means which permits it to rotate about an inclined axis, means for rotating the cylindrical member, means for delivering powdered sand and gold to one end of said cylindrical member, means for producing a strong blast of air through 75 the interior of the cylindrical member, a stationary frame supported by the first mentioned frame at the delivery end of the cylindrical member, a plurality of inclined, spaced, overlapping amalgamating plates secured to 80 the stationary frame, said plates having their amalgamated surfaces adjacent the cylindrical member and means for simultaneously tilting the plates about their longitudinal axes. 85 90

3. A dry placer mining machine for separating fine gold from dry nonmetallic material comprising, in combination, a cylinder mounted for rotation about an inclined axis, means for rotating the cylinder, means for introducing the material to be separated into the upper end of the cylinder, means for agitating the material as the cylinder is rotated, means for introducing an annular stream of air at high velocity into the upper 95 100 end of the rotating cylinder and a plurality of substantially parallel spaced overlapping plates closing the lower end of the cylinder, the sides of the plates adjacent the cylinder being amalgamated. 105

4. A dry placer mining machine for separating fine gold from dry nonmetallic material comprising, in combination, a cylinder mounted for rotation about an inclined axis, means for rotating the cylinder, means for introducing the material to be separated into the upper end of the cylinder, means for agitating the material as the cylinder is rotated, means for introducing an annular stream of air at high velocity into the upper 110 115 end of the rotating cylinder, a stationary frame located at the lower end of the cylinder and a plurality of substantially parallel spaced, slightly overlapping plates pivotally attached to the frame and means for rotating the plates about their axes. 120

5. A dry placer mining machine for separating fine gold from dry nonmetallic material comprising, in combination, a cylinder mounted for rotation about an inclined axis, means for rotating the cylinder, the interior 125 of the cylinder being divided longitudinally by two screens that intersect each other at

right angles so as to form four radial screens, means for introducing air into the upper end of the cylinder and directing it downwardly towards the lower end, a stationary frame located adjacent the lower end of the cylinder and a plurality of spaced plates extending across the open end of the cylinder, the sides

of the plates adjacent the cylinder being amalgamated.

In testimony whereof we affix our signatures.

WILLIAM F. COMBS.
ISAAC C. LIGHTFOOT.
